[57] CLAIM

The ornamental design for a cartridge for filtration or
absorption media, as shown and described.

DESCRIPTION

FIG. 1 is a side elevational view of a cartridge for filtration
or absorption media showing my new design; the
sides opposite and adjacent being identical in appear-
ance;

FIG. 2 is a top plan view thereof; and

FIG. 3 is a bottom plan view thereof.

FIG. 1

FIG. 2

FIG. 3
